US00D873265S

(12) **United States Design Patent** (10) **Patent No.:** **US D873,265 S**
(45) **Date of Patent:** **** Jan. 21, 2020**

(54) **ELECTRONIC DEVICE**

(71) Applicant: **Amazon Technologies, Inc.**, Seattle, WA (US)

(72) Inventors: **Timothy Eli Wall**, San Francisco, CA (US); **Marc Rene Walliser**, San Francisco, CA (US)

(73) Assignee: **Amazon Technologies, Inc.**, Seattle, WA (US)

(**) Term: **15 Years**

(21) Appl. No.: **29/610,134**

(22) Filed: **Jul. 10, 2017**

Related U.S. Application Data

(62) Division of application No. 29/560,832, filed on Apr. 11, 2016, now Pat. No. Des. 795,249.

(51) **LOC (12) Cl.** **14-02**

(52) **U.S. Cl.**

USPC **D14/341**

(57) **CLAIM**

The ornamental design for an electronic device, as shown and described.

DESCRIPTION

FIG. 1 is a front perspective view of an electronic device, showing the new design;

FIG. 2 is a back perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The broken lines depict portions of the electronic device that form no part of the claimed design.

1 Claim, 8 Drawing Sheets
